UNITED STATES PATENT OFFICE.

ROBERT L. DAVIS, OF PITTSBURGH, PENNSYLVANIA, ASSIGNOR TO WESTINGHOUSE ELECTRIC & MANUFACTURING COMPANY, A CORPORATION OF PENNSYLVANIA.

VARIABLE INDUCTOR.

Application filed September 7, 1926. Serial No. 133,811.

My invention relates to variable inductors, and it has particular relation to variable inductors adapted to be utilized as antenna loading coils.

5 One of the objects of my invention is to provide a variable inductor that will be self-supporting.

Another object of my invention is to provide an inductor that is capable of continuous variation.

10 Still another and more specific object of my invention is to provide an antenna loading coil that is capable of being easily and quickly installed and which has constants 15 that are not sensibly varied by changing weather conditions.

The antenna loading coils employed in the past have, in general, been constructed by winding a sufficient number of turns of conducting material upon a plurality of insulating supports. Inasmuch as these coils are usually exposed to the weather, when 20 in use, it is obvious that rain or snow will, to a certain extent, affect the insulation between the several turns. It has also been the custom with such loading coils to vary the inductance thereof by means of movable clips attached to a flexible conductor, the 25 clips being attached to suitable portions of the exterior of the coil.

30 In moving the clips from one position to another on the coil, the flexible leads therefrom tend to partially encircle the coil per se, adding to or subtracting from the effective inductance thereof, depending upon the direction in which the clip is moved. Under such circumstances, an accurate pre-determination of the inductance is practically impossible.

35 40 By my invention, I have entirely obviated the necessity of using a flexible lead to the movable, inductance-varying clip, substituting therefor a rigid rod. I further contemplate the use of rigid wire or tubing for 45 the loading coil itself, supporting the coil only from the opposite ends thereof.

The novel features which I believe to be characteristic of my invention are set forth with particularity in the appended claims.

50 My invention itself, however, both as to its organization and its method of operation,

will best be understood by reference to the following description, taken in connection with the accompanying drawings.

Fig. 1 is a side elevational view of a preferred embodiment of my invention. 55

Fig. 2 is an end elevational view of the same.

Fig. 3 is a detail view of an alternative form of contact device. 60

Referring specifically to Figs. 1 and 2, a helix 1, constructed of wire or tubing sufficiently strong to be self-supporting, is maintained in position by having the ends 2 and 3 thereof clamped to insulating supports 4 and 5 by means of clamping devices 6 and 7. An extension 8 of the insulating support 5 carries an adjustable clamping device 9 through which passes a rigid conductor 11. The conductor 11 projects into 70 the interior of the helix 1 and, at its inner end, it terminates in a bent portion 12, on the extreme end of which is a device 13 adapted to make contact with the inner surface of the helix 1. 75

The rigid conductor 11 is rotatable and 80 slideable in the clamping device 9, permitting the contact device 13 to be positioned at any point on the helix.

When it is desired to change the effective 85 inductance of the helix, the clamping device 9 is loosened, permitting the rigid conductor 11 to move freely therein. By a proper manipulation of the conductor 11, the end contact element 13 may be moved along the 90 helix to a predetermined position, it being obvious that, as the contact element rotates about the axis of the helix, the rigid conductor will pass longitudinally through the clamping device. 90

Under certain conditions, it may be desirable to permanently fix the position of the contact element 13 on the helix, and, for this purpose, a contact element of the type illustrated in Fig. 3 may be employed. The bent portion 12 of the rigid conductor 11 may terminate in a clamping device 14 comprising a fixed element 15 attached to the conductor and a movable element 16, the two 95 being held together by an adjusting screw 17. Each of these elements is provided with 100 a channel, the two channels defining a space

18 to receive the helix 1. By loosening the adjusting screw 17, the two portions of the clamping device may be separated sufficiently to permit movement of the helix there-through, the finally determined position being maintained by a tightening of the screw.

The contact device, in addition to its primary function, has the additional function 10 of supplying added support to the helix. This additional support is of importance when the helix attains a considerable length.

It is believed to be apparent to those skilled in the art that my invention is not 15 confined to antenna loading coils but that it may equally as well be applied to solenoids of the type ordinarily used as loose-couplers, or to the tuning coils customarily employed in radio receiving and transmit- 20 ting sets.

The principal advantage attending the use 25 of my invention results from the fact that the inductance of a helix may be changed without involving the uncertainty introduced by the customary flexible lead. The rigid conductor of my invention maintains a fixed axial relation to the helix, and the variation 30 in length of the conductor has a negligible effect on the total inductance. In addition, it will be noted that the contact element may be moved around the entire inner circumference of the helix without disconnecting and replacing the same, as is the case 35 when the customary movable clip is applied to the outer surface of the helix. The likelihood of leakage from the flexible conductor to adjacent portions of the apparatus is avoided, such leakage being a matter of importance when high potentials and frequencies 40 are employed.

While I have shown but one specific embodiment of my invention, it is not my intention to be limited thereby. My invention is accordingly not to be limited except in so 45 far as is necessitated by the prior art and by the spirit of the appended claims.

I claim as my invention:

1. An inductance device and a three-point support therefor, one of said supports being

positioned in the interior of said device and 50 being movable axially thereof.

2. A spirally-wound inductance device, supports to which the ends of said inductance device are secured, a conductor located axially within said inductance device, means by 55 which said conductor may make contact with the inductance device, and clamping means permitting axial and rotary movement of said conductor.

3. An inductance device, a conducting 60 member, means for supporting such member in the interior of said inductance device, circumferentially adjustable means for making electrical contact between said member and the inductance device, and clamping 65 means carried by said contact member for fixing its position relative to said inductance device.

4. In combination, a plurality of insulating supports, an inductor carried therebetween, a clamp carried by one of said supports, a conducting member held by said clamp and positioned within said inductor, and means carried by said conductor for making electrical contact with the interior of 75 said inductor.

5. A variable inductance device and a plurality of supports therefor, one of said supports constituting the variation means, and means carried by said last named support for 80 securing it in adjustable relation to said inductance device.

6. In combination, a plurality of insulating supports, an inductor carried therebetween, a clamp carried by one of said supports, a conducting member held by said clamp and positioned within said inductor, and means carried by said conducting member for making electrical contact with the interior of said inductor, said last named 85 means being capable of securing said conducting member to said inductor at any desired point thereon.

In testimony whereof, I have hereunto subscribed my name this first day of September, 1926.

ROBERT L. DAVIS.
